(57) **CLAIM**

The ornamental design for a gaming robot, as shown and described.

DESCRIPTION

FIG. 1 is a front view of the gaming robot showing the new design;

FIG. 2 is a rear view thereof;

FIG. 3 is a left side view thereof;

FIG. 4 is a right side view thereof;

FIG. 5 is a top side view thereof;

FIG. 6 is a bottom side view thereof; and,

FIG. 7 is a perspective view thereof.

The broken lines showing of the gaming robot is for the purpose of illustrating portions of the article that form no part of the claimed design.
